UNITED STATES PATENT OFFICE.

WILLIAM PETERSON, OF ANAHEIM, CALIFORNIA.

WRENCH.

Application filed July 1, 1927. Serial No. 202,862.

This invention aims to provide a simple three-piece wrench embodying novel means for holding the movable jaw in adjusted positions with respect to the fixed jaw.

5 Figure 1 is a side elevation; Figure 2 is an elevation wherein the wrench is viewed edge-wise; Figure 3 is a section showing one side of the movable jaw; Figure 4 is a section showing the opposite side of the movable jaw; 10 Figure 5 is a section on the line 5—5 of Figure 1; and Figure 6 in a section on the line 6—6 of Figure 1. In all the views, parts of the handle are broken away.

The wrench includes a body 1, made up of a handle 2, an enlarged head 3 on the handle, and a fixed jaw 4 on the head. There is a slot 5 in the head, across which the jaw 4 extends, the jaw serving as a connection between side wings 6 and 7 that are formed by the slot 5. 20 On the inner surface of the flange 6 there is a guide groove 8. The flanges 6 and 7 have lines of coaxial holes 9, the lines of holes being parallel to the groove 8. The flange 7 has an off-set external lip 10 defining an elongated 25 seat 11, the lip and the seat being disposed parallel to the guide groove 8.

The movable jaw is marked by the numeral 12 and has a thinned fin 14 which slides in the slot 5 in the head of the wrench, the fin forming shoulders 15 on each side of the fin, the shoulders sliding on the edges of the flanges or wings 6 and 7. The fin 14 has a rib 16 which is received slidably in the guide groove 8. The fin 14 is provided with openings 17 adapted to register, one at a time, with the 30 holes 9 in the body of the wrench.

The movable jaw 12 is shifted toward and from the fixed jaw 4, until the required adjustment has been obtained, and then a tapered securing element (pin) 18 is inserted through the openings 17 and 9 which happen to be aligned. The securing element or pin 18 has a handle 19 which swings parallel to the wing 7, in contact with the body of the 40 wrench. The handle is supplied, on opposite sides of the axis of the pin 18, with projecting fingers 20 which are beveled as shown at 21 to

form cams which, when either one of the fingers 20 is engaged beneath the lip 10, crowd the tapered pin 18 into the holes 17 and 9, to hold the movable jaw 12 in the position to which it has been adjusted. It is possible to swing the handle 19 into such a position that neither of the fingers 20 will be engaged under lip 10, and then the pin 18 can be removed 50 to permit the movable jaw 12 to be shifted with respect to the fixed jaw 4. There is an advantage in having the duplicated, oppositely disposed, fingers 20. When the pin 18 is in a position near to the right hand end of the line of holes 9 in Figure 1, one of the fingers 20 may be engaged beneath the lip 10, with the handle 19 to the left; and when the pin 18 is mounted near to the left hand end of the 55 row of holes 9 in Figure 1, the other finger 20 can be engaged under the lip 10, with the handle 19 extending to the right; and in this way, the handle 19 can be so placed that it will not stick out beyond the edge of the head 60 of the wrench.

What is claimed is:—

A wrench the body of which has a fixed jaw and an elongated external lip, a movable jaw cooperating with the fixed jaw and slidable on the wrench body, the body and a part of the 75 movable jaw having holes adapted to be brought into registration, and a pin insertible into the holes and provided with a handle, the handle being provided on each side with a finger, either finger being engageable under the 80 lip, to hold the pin in place, the provision of two fingers permitting the handle to be turned in opposite directions, thereby to prevent the handle from projecting beyond the 85 edge of the wrench when the pin is located near to one edge of the wrench, the edges of the fingers being so inclined with respect to each other that either finger may be disengaged from the lip, thereby to permit the pin 90 to be withdrawn.

In testimony that I claim the foregoing as my own, I have hereto affixed my signature.

WILLIAM PETERSON.
